United States Patent Office

Des. 186,136
Patented Sept. 15, 1959

186,136

HOLDER FOR A RAZOR BLADE

Walter Czerwinski, Toronto, Ontario, Canada, assignor of fifty percent to Wilfred Taylor, Ontario, Canada

Application March 20, 1958, Serial No. 50,107

Term of patent 14 years

(Cl. D58—12)

Figure 1 is a perspective view of a holder for a razor blade showing the bottom, one side and end, embodying my new design; and

I claim:

The ornamental design for a holder for a razor blade, as shown.
